UNITED STATES PATENT OFFICE

2,676,750

FLAT FOLDED CARTON

Frank A. Gastright, Fort Thomas, Ky., assignor to The Queen City Manufacturing Co., Cincinnati, Ohio, a corporation of Ohio

Original application June 3, 1950, Serial No. 165,989. Divided and this application March 15, 1951, Serial No. 215,670

4 Claims. (Cl. 229—39)

1

This application is a division of my co-pending application Serial No. 165,989 filed June 3, 1950. My present invention relates to cartons or containers of the type employed in conjunction with bulk dispensing vending machines, such as the machine disclosed in the aforementioned application wherein a supply of the cartons or containers, in flat folded condition, are stored within a hopper of the machine. The cartons employed are of the conventional four panel side wall structure with automatic self-locking bottom flaps as shown in the U. S. Patent No. 2,388,190, which flaps become interlocked upon erection of the carton and thus retain the carton in its erected position, no top closure flaps or panels being required. As well known these four wall cartons in their flat folded condition may readily be squared up, or erected, by applying pressure (a squeezing action) on the opposite flat folded edges of the structure.

Each time a customer deposits a coin in the machine a mechanism is activated which functions to extract one of the flat folded cartons from the hopper, pushing the carton forward in its flat folded condition. As the carton is thus pushed forward its leading flat folded edge strikes an abutment which prevents further forward movement at that edge of the carton. However, the pushing action, at the trailing flat folded edge, continues and thus contributes to a squeezing action which results in the flat folded carton being spread to its squared up and erected position. Just as this operation is completed another mechanism within the machine operates to dispense a portion of bulk merchandise into the erected carton, the merchandise falling through a suitably positioned discharge orifice located above the carton.

In machines of this character wherein, with each dispensing operation, a flat folded carton must be extracted from a hopper and advanced to its squared up erected position, various difficulties have heretofore been encountered. One difficulty has been due to irregular thickness of the flat folded carton which irregularity is caused by the various plies of paperboard stock in the flat folded structure. Among other objections this irregular thickness has caused difficulty in extracting but one carton at a time from the hopper. Another difficulty has been due to uncertainty of an extracted flat folded carton to properly open and spread to its erected position as required, the cartons tending to buckle or fold instead of opening as required.

With the above in mind it is an object of my

2

invention to provide an improved carton wherein undue variations in thickness of the flat folded structure are reduced by means of scored indentations in the paperboard stock.

Another object of my invention is to initiate and assure proper spreading and erecting of the carton to its squared up position by means of a notch, or cut-out portion, located in the upper margin of one of the leading side wall panels, and a slit located in the upper margin of the flat folded trailing edge. The notch, as the carton is pushed forward, permitting entry of a stationary blade between the flat folded carton walls to thus positively prevent undesired buckling or folding of the carton structure and to initiate proper spreading and erection as the squeezing or erecting action to open up the carton for receiving its charge of dispensed merchandise takes place. The slit, in the trailing flat folded edge, permits the exit of the blade as the carton is pushed forward to its fully erected position.

Other objects of my invention will be apparent as the description proceeds.

25 Referring now to the drawings:

Figure 1 is a plan view of a box blank which has been cut, scored and indented in accordance with my invention.

Figure 2 is a plan view of the box in its final flat folded and glued condition, ready for use in a dispensing machine.

Figure 3 is an enlarged fragmentary sectional view taken along the line 3—3 of Figure 1.

Figure 4 is an enlarged fragmentary sectional view taken along the line 4—4 of Figure 2.

Figure 5 is an enlarged fragmentary sectional view taken along the line 5—5 of Figure 2.

Figure 6 is a fragmentary perspective view showing the upper end of my improved carton in slightly opened position.

Figure 7 is a diagrammatic perspective view illustrating a preferred arrangement of an extractor for pushing a flat folded carton forward from a hopper; a stationary blade for assuring and initiating proper spreading and erecting of the carton; and an abutment against which the leading edge of the carton abuts while the pusher member continues to move forward to press the carton to its squared up and finally erected position as indicated in dotted lines.

As indicated in Figure 1, the main body portion of the carton blank has sidewall panels 10, 11, 12 and 13 joined by foldable score lines 14, 15 and 16. A glue flap 17 is joined by score line 18 to the panel 13.

Bottom closure flaps or panels 19, 20, 21 and 22 are articulated to the sidewall panels by score lines respectively indicated at 23, 24, 25 and 26. As herein shown the bottom closure flaps 20 and 22 are respectively provided with notches 20a and 22a. The flaps 20 and 22 also have diagonally disposed foldable score lines 20b and 22b, the line 10 divided the panel 20 into portions 20c and 20b dividing the panel 22 into portions 22c and 22d. Likewise the line 22b divides the panel 22 into portions 22c and 22d.

The bottom closure flaps herein shown and just above mentioned are of the automatic, self-erecting and self-interlocking type such as disclosed in U. S. Patent No. 2,388,190. A complete detailed description regarding arrangement and 15 operation of these flaps is not included in this specification, reference being made to the said patent. However, it is to be understood that other types of carton bottom closures may be 20 readily substituted without affecting the utility of my invention.

Within an upper margin of the main body portion and in the sidewall 10 is a cut-out portion or notch 27. Also within the same upper margin is a slit or line of cut 28, in alignment with the score line 16. Formed within a deeper upper margin of the blank are lines of indentation 29 and 30 respectively located in panels 12 and 13, the lines of indentation being equally spaced from the slit 28.

During the operations of folding and gluing the blank of Figure 1 to produce the flat folded carton structure of Figure 2, adhesive is applied to the glue flap 17 as indicated at 17a. Other spots of adhesive 20e and 22e are applied respectively to the panels 20c and 22c.

Referring now to Figure 2 it may be pointed out that sidewall panel 13, together with glue flap 17, have been folded inwardly about the score line 16 to a position overlying the panels 12 and 11. The sidewall panel 10 has been folded about the score line 14 to a position overlying the panel 11, a marginal portion of the panel 10 becoming adhered to the glue flap 17. The bottom flaps 19 and 21 have been folded upward intermediate the carton sidewalls and the bottom flaps 20 and 22 have likewise been folded upward, but with their portions 20c and 22c (to which adhesive is applied) folded reversely. Thus the bottom flaps 19 and 20 are adhered together, by means of the panel 20c. Bottom flaps 21 and 22 are likewise adhered together by means of the panel 22c.

Due to natural reaction of folded paperboard stock the thickness of any flat folded carton is slightly increased along the lines of flat (or 180°) fold, such as the fold line 16. Thus in the vicinity of the slit 28 the folding reaction is eliminated and reduction of thickness results throughout the length of the slit. This loss of thickness creates an irregularity in the flat folded edge of the carton, which irregularity may interfere with proper feeding of the carton from the supply hopper. Referring now to Figures 2 and 4, it will be observed that in the flat folded position of the carton the lines of indentation 29 and 30 abut each other increasing the thickness between panels 12 and 13. Thus the indentations serve to compensate for loss of thickness due to presence of the slit 28 and proper feeding of the cartons is obtained.

Referring now to Figure 7, a flat folded carton 50 has been extracted from a hopper (not shown) and is being pushed forward (in the direction of arrow X) by means of a blade or pusher 51 which 75

engages the flat folded edge 16 of the carton. Means for actuating the pusher 51 and other means for guiding the carton are not here shown, being no part of my present invention. Suitable means for these purposes are, however, disclosed in detail in my aforementioned copending application.

As the carton 50 is thus pushed forward, a stationary blade 52, preferably bent somewhat as at 53, engages the notch 27 and enters between the sidewalls 10 and 11 of the flat folded carton. As the carton continues to move forward, the blade 52 also passes between the carton walls 12 and 13. The blade 52 may have a gradual flared formation terminating in the enlarged end 54, and as this end 54 passes through the notch 27 the blade 52 will be positioned between the carton sidewalls 10 and 13 on one side, 11 and 12 on the other side. As the carton moves on the leading or bent end 53 of the blade emerges through the slit 28 in the trailing edge 16 of the carton. As this occurs, the flared portion of the blade 52, now passing between the carton walls 12 and 13, initiates or 25 commences a spreading action preparatory to final and complete erection of the carton. Just as this initial spreading occurs, the leading flat folded edge 14 of the carton strikes an abutment 55 and further forward travel of the carton is 30 prevented. However, the pusher 51 continues to move forward pressing against the trailing edge 16 of the carton until the carton is pressed to its squared up and fully erected position indicated at 56, whereupon the self-erecting bottom flaps become interlocked to retain the carton in erected 35 position and the pusher blade 51 retracts to a rear position in readiness for its next operation.

It is not a requirement that the blade 52 is of flared formation. The mere presence of a flat blade positioned between the walls of a flat folded 40 carton is sufficient to initiate a slight spreading action, prevent buckling and contribute to proper opening of the carton.

The length and arrangement of the blade 52 may be such that the blade exits from the slit 28 just as the carton is brought to its fully erected 45 position. As shown in the diagram, however, the blade is not fully withdrawn from the carton, complete withdrawal occurring when the customer manually removes his purchase. Thus the blade serves an additional advantage in that the erected carton is less likely to become displaced, prior to or during discharge of merchandise into the carton.

Modifications of my invention will readily 55 occur to those skilled in the art and it is to be understood that I am not to be limited to the precise structure shown and described.

Having thus described my invention, what I 60 claim to be new and desire to secure by Letters Patent is:

1. In a carton for use in a bulk merchandise dispensing machine wherein a flat folded carton is pushed to erected condition by pressure means acting on a folded edge of the carton, and wherein a blade is provided to enforce the separation of the carton walls as it is being pushed, a collapsed tubular body comprising four body walls in articulation, closure flaps articulated to the bottom edges of said body walls, said closure flaps adapted to be automatically erected and interlocked upon erection of the carton, said tubular body being in flat folded condition with the line of articulation between an adjacent pair of body walls forming the leading edge of the 65 flat folded carton, and the line of articulation 70

between the remaining two body walls forming the trailing edge of said flat folded carton, said first mentioned pair of body walls being the leading body walls, and the remaining pair the trailing body walls, a cutout contiguous with the top edge of one of the leading body walls for receiving the blade for separating said walls, and a line of cut along the top edge of the trailing edge of said carton for permitting passage of the blade through the rear of the carton, and a pair of mating, inwardly directed indentations in the trailing walls, one on each side of said trailing edge, for maintaining said trailing walls slightly spaced from each other when in flat folded position.

2. The structure claimed in claim 1 wherein said cut-out in said leading wall is positioned intermediate the ends of said wall.

3. The structure claimed in claim 1 wherein said mating indentations comprise score lines 20 extending downwardly from the upper edges of said trailing body walls in substantial parallelism with said line of cut.

4. A carton for use in a bulk merchandise dispensing machine wherein a flat folded carton 25 comprising a flattened collapsed tubular body having four enclosing body walls in articulation is pushed forward and erected by pressure applied

to opposite leading and trailing flat folded edges, a cut out opening contiguous with the top edge of one of the leading body walls, and a line of cut along the line of articulation of the trailing flat folded body walls, said line of cut extending downwardly from the top edge of said line of articulation, and lines of indentation in the body walls adjacent said line of articulation, said lines of indentation being equally spaced from said line of articulation whereby said last mentioned body walls are maintained slightly spaced from each other when said carton is in flattened collapsed position.
